UNITED STATES PATENT OFFICE.

CHARLES B. ANDREWS, OF HIGH BRIDGE, NEW JERSEY, ASSIGNOR TO TAYLOR-WHAR-
TON IRON AND STEEL COMPANY, OF HIGH BRIDGE, NEW JERSEY, A CORPORA-
TION OF NEW JERSEY.

DIPPER TOOTH.

Application filed February 14, 1925. Serial No. 9,230.

To all whom it may concern:

Be it known that I, CHARLES B. ANDREWS, a citizen of the United States, residing at High Bridge, in the county of Hunterdon and State of New Jersey, have invented certain new and useful Improvements in Dipper Teeth, of which the following is a specification.

My invention provides certain improvements in two part reversible digging teeth, commonly known as dipper teeth.

For a number of years it has been the practice to construct the point and base of manganese steel because of the remarkable wear resistance that metal exhibits when its inherent characteristic of toughness combined with hardness is fully developed by proper heat treatment. Many methods of attaching the point or wearing tip to the base have been proposed. Some of them are good, but many are entirely impracticable because they do not take into account the necessity for providing substantially uniform metal sections to insure sound castings and proper heat treatment, nor recognize the impossibility of regularly obtaining close interchangeability of parts when making rough castings of a non-machinable steel.

My improvements are the result of extended practice in the designing of excavating apparatus and close observation of the behavior of digging teeth in all classes of service and under all kinds of operating conditions. They were devised with the following objects in view, to wit:—to simplify the lock between point and base while maintaining substantial uniformity as regards metal sections; to insure a tight fit by eliminating conditions making for premature contact; to eliminate excess or unnecessary metal in the point; to reinforce the nose of the base so that it will resist side thrust of the point with a minimum resultant of spreading or breakage; and to provide a wedge bolt of such form that it not only has greater shear resistance, but compensates for unavoidable mislocation of cored holes, and is fool-proof in the sense that it can be applied in the correct way only.

With such and other objects in view, the nature, characteristic features and scope of the invention will more readily be under-

stood from the following description taken in connection with the accompanying drawing, wherein—

Figure 1 is a top view partly in section of a two part reversible tooth embodying my improvements;

Figure 2 is a side elevational view of the same;

Figure 3 is a perspective view partly in section of the point; and

Figure 4 is a perspective view of the wedge bolt.

In the drawing, 5 represents the base and 6 represents the detachable and reversible point. These elements, save in the particulars hereinafter noted, are or may be as usual.

According to my invention, the slotted or bifurcated nose portion of the base is reinforced without unduly massing the metal by means of integrally cast or formed upper and lower ribs 7 and 8. The ribs preferably converge at the front, as at 9; are continued rearwardly preferably beyond the division 10 of the base, and ultimately vanish in the body of the base. On bases of small size the lower ribs may be omitted, when there would otherwise be interference with the operation of a wrench on the nut. The merit of the ribbed construction is that it provides increased resistance to side thrust under digging strains, prevents spreading and eventual breakage of the nose, and acts as a guard to protect the nut from abrasive wear in service.

The jaws of the point are joined by a web 11 that fits the slot 12 of the base. Departing from the usual practice, the web, while of nearly the full depth of the jaws, is cut away as at 13, so as to eliminate unnecessary metal and so as to provide a flat bearing surface 14 for a purpose hereinafter referred to, the cut out portion being of general diamond shape.

The general design, with respect to the fit of the point and base, is such that initially there is clearance at the tip of the nose, as indicated at 18. This is an important feature because without such clearance there would be the usual premature contact which prevents or seriously interferes with proper seating of the point. The clearance enables

the taper bolt or tightening device properly to seat the point and to tighten it from time to time as is necessary in service. It not infrequently happens in teeth of earlier designs that the cored holes for the bolt are out of alignment and when the ordinary wedge bolt is applied to a condition of this kind it shifts the point until the holes register, which puts side shear on the bolt and results in uneven pressure between the top and bottom fit of point and base. Moreover, the old style bolt can be, and in service frequently is used in reverse position; which naturally prevents proper wedging action and causes looseness of the point in a short time. This brings us to another important feature of the invention, namely the means for initially and continuously properly seating the point and for keeping it tight in service. In providing this feature and while utilizing the principle of the wedge, I materially depart from the usual wedge bolt, which has two rounded edges and hence is capable of reversal and destructive influences as already pointed out. The wedge bolt 15 of my invention has a flat edge 16 on the side parallel to the axis of the threaded end. Its tapered side 17 is rounded. The cored openings 19, 20 in the nose correspond to the cross-section of the bolt. The wedge bolt 15 is therefore fool-proof in the sense that it can be applied but one way—the correct way. Moreover it is immaterial whether or not the cored holes are in register because the flat edge of the bolt bearing on the flat surface of the opening in the web, allows for shift and compensates for unavoidable mislocation of bolt openings while at the same time providing greater shear resistance. Referring to Figs. 1 and 3, it will be apparent that the flat edge of the bolt takes a flush bearing at all times against the central flat bearing surface 14 in the cut away portion of the web. Evidently then, in my construction, the point must take the correct central position on the base, and it follows that the bolt can be entered and driven home regardless of the location of the cored holes in the base.

What is claimed is:

1. A dipper tooth embodying a base bifurcated for the reception of a point, a point capable of reversal thereon, and means for tightening the point, the point and base having relative clearance at the extreme nose portion of the base for the purpose and with the result of insuring correct seating of the point in response to tightening effort.
2. A dipper tooth embodying a base bifurcated for the reception of a point, a point capable of reversal thereon, and non-reversible means for tightening the point, the point and base having relative clearance at the extreme nose portion of the base for the purpose and with the result of insuring cor-

rect seating of the point in response to tightening effort.

3. A dipper tooth embodying a base and a detachable point with openings for the reception of a wedge bolt for relatively securing them, and a non-reversible wedge bolt.

4. A dipper tooth embodying a base and a detachable point whereof both are constructed with bearing surfaces for a tightening element, and a tightening element co-operating with said bearing surfaces and shaped so as to be non-reversible and effective properly to seat the point.

5. A dipper tooth embodying a base and a detachable point, said elements having openings for a tightening device, and a tightening device effective to seat correctly the point regardless of casual misalignment of the openings.

6. A dipper tooth embodying a base and a detachable point, and a wedge bolt for relatively securing them, the wedge bolt having a flat edge bearing surface parallel to the axis of the threaded end and a rounded taper bearing surface, the openings in the base being correspondingly formed, whereby the bolt is applicable one way only.

7. A base having a bifurcated nose whereof each half is of channel cross-section.

8. A base of the bifurcated nose type, each nose element being of channel cross-section, said section stopping short of the tip of the nose and vanishing in the body of the base beyond the division thereof.

9. A base having a bifurcated nose whereof each half is provided on its outer side wall with marginal ribs to enable the nose effectively to resist side thrust incidental to digging.

10. A base having a bifurcated nose whereof each half is provided with laterally directed edge reinforcements to stiffen the nose against side thrust, said reinforcements converging at the front and continued rearwardly beyond the division of the base.

11. A dipper tooth embodying a base having a bifurcated nose, a detachable point having a web which enters said nose and which initially clears the frontal extremity of the nose, a point tightening element of the non-reversible wedge type, and bearings in the point and base and co-operating with the tightening element to take up the clearance and compel correct central positioning of the point.

12. A point having web connected jaws, the web having a slot of general diamond shape and whereof the extreme rear wall defines a flat bearing surface for a tightening element.

13. A wedge bolt for dipper teeth, having a flat edge bearing surface parallel to the axis of the threaded end and a rounded taper bearing surface.

14. A point having a central web formed

with a longitudinal slot, the extreme rear wall of which defines a flat bearing surface for use in centering the point.

15. A point having a central web formed with a longitudinal slot, the extreme rear wall of which is limited vertically and defines a flat bearing surface for use in centering the point.

16. A dipper tooth, embodying a base and 10 a reversible point constructed and arranged

for relative fit without premature contact, a wedge bolt co-operating with the point and base for application one way only, whereby it correctly seats the point with a minimum of shearing strain, and means 15 formed integral with the base to augment its resistance to side thrust and effective to shroud the ends of the bolt.

In testimony whereof I affix my signature.

CHARLES B. ANDREWS.
